UNITED STATES PATENT OFFICE.

HENRY COWLES AND JAMES K. NORRIS, OF UTICA, NEW YORK, ASSIGNEES TO UTICA
HEATER COMPANY, OF WHITESTOWN, NEW YORK, A CORPORATION OF NEW YORK.

SECTIONAL FURNACE.

Application filed January 11, 1923. Serial No. 612,005.

Our invention relates to a sectional furnace made up of an assembled series of hollow water-containing sections forming a fire box and flue space and including novel 5 means for introducing auxiliary air to the fire box near the front of the furnace to promote completeness of combustion and prevent or minimize smoke, and to the structure of the front section or sections whereby 10 the results stated are accomplished.

Referring to the drawings: Figure 1 is a side elevation of a sectional furnace embodying our invention, parts of the side walls of the sections being broken away to 15 show the internal construction in section.

Figure 2 is an elevation of the front section and of the second section, parts of the front wall of the front section being broken away to show the structure in rear thereof 20 partly in elevation and partly in section, and part of the front wall of the second section being broken away to show internal construction in section.

Figure 3 is the section on the line 3—3 25 of Figure 2 looking in the direction of the arrows.

Figure 4 is a perspective of the apertured channel bar, which constitutes one of the walls of the auxiliary air delivery passage, 30 and

Figure 5 is a detail side elevation showing the inlet of the auxiliary air delivery passage with its adjustable damper.

The furnace in which our invention is 35 illustrated as embodied is made up of a series of hollow water-containing sections 1 bolted together in the customary way and suitably supported as by the base members 2 at each side thereof, these members with 40 transverse rear plate 3 and front plate 4 enclosing space beneath the sections, part of which divided off by the plate 5, forms the ash pit. The front plate 4 has the usual door and damper arrangements which need 45 not be particularized. By their aligned openings sections toward the front of the furnace provide the firebox 6, intermediate sections combustion and flue space 7 communicating therewith, and rear sections flue 50 space 7 and means of communication with the overhead side return flues 8, both of which deliver to escape flue 9. None of these sections requires special consideration or description except the front section 1^a, 55 which in the furnace illustrated, contains the

novel features which characterize this section itself and co-operate with other furnace elements. The section 1^a is provided with an opening 10 constituting the fuel entrance to the firebox and closed by the feed door 11. It is also provided with clean out openings and doors 12, said openings being separated by a vertical water-containing partition 13. The doors 12 each cover the end of the corresponding side flue 8 and part of the common escape flue 9 thereby giving access to all parts of both the side flues and the escape flue. Introduction of auxiliary air near the front of the firebox, and particularly near the upper part of it, as contemplated herein, has the advantage of giving increased opportunity for combustion during the passage of the air along with the fire gases through the entire length of the firebox so that its utilization for purposes of combustion due to the longer travel is the more complete. It is further desirable that the auxiliary air passage by which air is conveyed to the firebox and delivered therein should be formed in one of the sections 75 adjacent the front of the furnace and preferably in the front section itself, although a construction in which it is formed part in one section and part in the adjacent section will produce substantially equivalent 80 results. The air delivery passage 14 is best cast therefore, as an open-sided horizontal groove in the rear face of the front section 1^a above the feed door. As thus formed its 85 walls are water-cooled on three sides. Its open side, which faces toward the rear of the furnace is covered by a removable member 15 which most conveniently takes the form of an angle bar having air outlet openings 16. This bar is preferably suspended 90 by its upper flange 17 from the shoulder 18 extending across the rear side of the front section below flue space, where such shoulder forms a support receiving said flange.

Suitable inlet thimbles or bushings 19 are 100 located in openings cast in the side walls of the front unit, extending through the water space and communicating with the ends of the air delivery passage 14. These bushings are provided with dampers 20 whereby the auxiliary air supply is controlled. By the construction described, the auxiliary air delivery passage is adequately protected and the air passing through it is thereby heated 105 sufficiently so that it can take its intended 110

part in perfecting combustion in the firebox. In view of the fact above referred to, that air entering near the front of the firebox is in contact, for a longer time, with the burning gases, its heat on admission need not be so great as where delivered further toward the rear of the firebox. It will be noted also that advantage is taken of the usual configuration of front units in sectional furnaces, wherein there is a furnace opening, and, above the same, flue openings with an intermediate transverse, hollow water-cooled portion between, by locating the air delivery passage in the said intermediate transverse water-cooled portion. This requires the least possible departure from usual construction and merely involves casting a recess in the back face of the intermediate member of the front section. The rear wall of the passage thus formed is maintained in position without the necessity of special fastenings, and since there is sufficient room between opposed parts of the first two sections, may readily be removed or replaced. It is however made in two or more lengths as indicated for convenience of manufacture.

Claims:

1. A sectional furnace made up of an assembled series of cast hollow water-containing sections, the front section having a feed door and forming with adjacent sections the firebox, intermediate sections completing the firebox and forming combustion and flue space, and rear sections forming flue space, the various sections being provided with overhead flues in communication

with the flue space, and a transverse water-cooled passage cast in the body of the front section between the feed door opening and the overhead flue space and through which in the usual operation of the furnace auxiliary air is delivered in the firebox. 40

2. A sectional furnace made up of an assembled series of cast hollow water-containing sections, having aligned openings forming a firebox and flue spaces in connection therewith, the front section being provided with the usual furnace opening and feed door and having in its body a cast channel facing rearwardly and having its walls water-cooled, and a channel bar closing its rear open side and provided with a series of openings through which auxiliary air is delivered, rearward into the firebox. 50

3. In a sectional furnace, a cast hollow water-containing front section having feed and clean out openings and doors therefor and having walls enclosing respectively firebox space in the lower part of the section and flue space in the upper part and providing between said spaces a transverse member in which is cast a three channel structure extending lengthwise of the transverse member and comprising a pair of spaced water channels facing the front of the furnace and an open-sided air channel facing the rear of the furnace interposed between the water channels. 55

In testimony whereof, we have signed this specification.

HENRY COWLES.
JAMES K. NORRIS.
